CLAIM

The ornamental design for a filter sheet support element, as shown and described.

DESCRIPTION

FIG. 1 is a perspective view of a filter sheet support element, showing my new design;

FIG. 2 is a top plan view thereof, the bottom plan view being identical thereto;

FIG. 3 is a right side elevational view thereof, the left side elevational view being identical thereto; and,

FIG. 4 is a front elevational view thereof, the rear elevational view being identical thereto.

FIG. 1

FIG. 2**FIG. 3****FIG. 4**
